[57] CLAIM

The ornamental design for a sun control pergola top, substantially as shown and described.

DESCRIPTION

FIG. 1 is a perspective view of the sun control pergola top from the front and above the pergola, with the environment shown in phantom outline;

FIG. 2 is a side elevational view;

FIG. 3 is a perspective view similar to FIG. 1, but on an enlarged scale, and having environment features omitted;

FIG. 4 is a perspective view of the pergola top from the front and below;

FIG. 5 is a perspective view similar to FIG. 3, showing a second embodiment of the pergola top, as viewed from the front and above; and

FIG. 6 is a perspective view showing the pergola top of FIG. 5 from the front and below.

The broken line showing of posts and ground in FIG. 1 is for illustrative purposes only and forms no part of the claimed design.

FIG. 3

FIG.4

FIG. 5

FIG. 6
